UNITED STATES PATENT OFFICE.

FRANK BEN LANTERY, OF SOUTH EASTON, MASSACHUSETTS.

CANDY-WRAPPI NG MACHINE.

1,418,659.

Specification of Letters Patent. Patented June 6, 1922.

Application filed August 19, 1919. Serial No. 318,539.

To all whom it may concern:

Be it known that I, FRANK B. LANTERY, a citizen of the United States, and a resident of South Easton, Massachusetts, (whose 5 post-office address is South Easton, Massachusetts,) have invented an Improvement in Candy-Wrapping Machines, of which the following description, in connection with the accompanying drawings, is a specification, 10 like letters on the drawings representing like parts.

My present invention relates to wrapping machines, and more particularly to improvements in machines for wrapping paper on 15 stick candy and the like.

Heretofore, stick candy has been generally wrapped by hand, as, due to the difficulty of handling the material, and the relatively unskilled labor employed in its manufacture, 20 the resultant product is not uniform, varying considerably as regards diameter and length and it has been found impossible to devise a machine that would successfully operate. To successfully operate from a 25 commercial standpoint, a wrapping machine for this class of goods should be capable of wrapping the paper on sticks of varying length and diameter, and twist the ends of the paper wrapping to securely enclose the 30 candy in the paper, both for the purpose of preventing the paper from unrolling, and for the sake of cleanliness. In my improved machine, I successfully meet these conditions by mechanism that sheers off the proper 35 length of paper and feeds the same to a device that simultaneously rotates the candy stick and wraps the paper thereon. At the completion of the wrapping, mechanism is brought into play to twist the ends of the 40 paper on the candy stick, and finally the wrapped stick is ejected from the machine.

An object of my invention therefore, is the provision of means for rolling a strip of paper on a stick of candy or the like.

Another object is an improved means for 45 twisting the ends of the paper wrapping to securely fasten the paper on the candy, and enclose the candy in the wrapping.

A further object is the provision of means 50 for severing an appropriate length of paper for each operation of the machine.

A still further object is the provision of improved means for simultaneously rotating a stick of candy or the like and wrapping 55 a protective covering thereon.

A further object is the provision of means

for removing the wrapped stick of candy from the machine.

Other objects and novel features and arrangements of parts will appear from time 60 to time as the description of the invention progresses.

In the accompanying drawings illustrating the preferred embodiment of my invention, 65

Fig. 1 is a plan view,

Fig. 2 is a side elevation, partly in section, 70 of a portion of the machine, showing the rollers and guides in position to receive a stick of candy,

Fig. 3 is a view, similar to Fig. 2, with a stick of candy in position to be wrapped,

Fig. 4 is a front elevation, partly in section,

Fig. 5 is a detail of the rolls and guides, 75 and

Figs. 6 and 7 are details of the end twisting means.

Referring to the drawings, 10 designates a base supported on front and rear legs 11 80 and 12 respectively. Rearward extensions 13 on the base 10 provide aligned bearings for a transverse shaft 14, receiving power from any suitable source, and on which is fastened a pulley 15.

Near the front of the base 10 and above the legs 11 are arranged shafts 16 and 17, 85 parallel to each other and to the shaft 14. Mounted on the shafts 16 and 17 and spaced apart from each other, are a plurality of wheels or pulleys 18, the periphery of said

wheels being grooved and equipped with rubber bands or tires 19, circular in cross section. The shaft 17 is provided with 90 wheels or pulleys 20, similar in number and arrangement to the wheels 18 on the shaft 16, each wheel 18 and 20 being centrally located with respect to the opposite pair of wheels 20 and 18 respectively. The distance between the shafts 16 and 17 is such 95

that with a given diameter of wheel 18 and 20, said wheels define a transverse trough or path in which a stick of candy 100 may lie during the wrapping operation. The shafts 16 and 17 are provided, at one end 100 thereof, with pulleys 21 and 22 respectively, and belts 23 and 24 connect the pulleys 21 and 22 respectively with the driving pulley 15. This driving connection between the pulleys 21 and 22, and the pulley 15 is such 105

that the shafts 16 and 17 are both driven in the same direction, with the result that the 110

stick of candy placed in the trough defined by the wheels 18 and 20, is rotated. Forward extensions 23^a and 24^a on the base 10, are provided with upstanding members, but 5 one of which, 25, is shown, screwed or otherwise secured to the extensions 23^a and 24^a. Fastened to and extending between the upstanding members is an inclined table 26, the rear end of which terminates adjacent 10 the trough defined by the wheels 18 and 20. At the extreme forward end and at each side of the table 26 are side plates 27 and 28, said plates being secured to the table by screws 29 passing through right-angled 15 extensions 30 and 31 on the front ends of the plates 27 and 28, respectively. The major portion of the side plates is left free, as clearly shown in Figs. 2 and 3, and, the side plates being made of resilient material, 20 as spring brass or the like, the distance between the side plates may be increased or diminished, depending on the length of the sticks of candy 100. It will be noted, by reference to Figs. 1 and 2, that the passage- 25 way exists between the table 26 and the side plates 27 and 28, and through which a strip of wrapping paper 32 may be fed diagonally across the table and into engagement with the wheels 18. An upward projection 30 33 on the rear end of the base 10 provides a bearing for a stub shaft 34, on which is mounted the forwardly extending arm 35, to the front end of which is fastened, by screws 36, or in any other suitable manner, 35 a cutter 37 which co-acts with an edge of the table 26 to form a cutting device for severing suitable lengths from the strip 32 of wrapping paper. On the arm 35 near the rear end thereof, is pivotally attached the 40 upper end of a depending link 38, the lower end of which is pivotally attached to a link 88 fastened to a shaft 39 mounted in bearing extensions 40 on the rear side of the legs 11. Intermediate the ends of the link 45 88 is pivotally attached the upper end of a rod 41, which extends downwardly to a treadle (not shown) and by means of which the link 88 and parts associated therewith are operated.

50 Extending between the legs 12 and the members of the base 10 are rods 43 and 42, which have attached to and support the rearwardly and downwardly inclined table or runway 44. Rotatably mounted on the 55 shaft 17, near each end thereof, are crank arms 45, and extending between and fastened to said crank arms is an extension 46 of the inclined table or runway 44 and also a plurality of curved arms 47. The 60 width of the arms 47 is such that they fit between adjacent wheels 18 and 20, and the curvature is equal to the radius of the stick of candy 100 to be operated on. Pivotedly attached to one of the crank arms 45 is the 65 lower end of an upwardly extending link

48, the upper end of which is provided with an elongated slot 49 which engages with a pin 50 on the arm 35.

Rotatably mounted on the shaft 14 at each end thereof, are bell crank levers having 70 long forwardly extending arms 51 and short upwardly extending arms 52. At the forward ends of the arms 51 is rotatably mounted a shaft 53 on which is mounted a plurality of wheels 54, similar in character 75 to the wheels 18 and 20, said wheels 54 being spaced apart on the shaft 53 and are equal in number to the total number of wheels 18 and 20. A pulley 55 on one end of the shaft 53 is connected by a belt 56 to 80 the pulley 15. Pins 57 in the arms 51 provide stops for the plate 58, pivotally mounted on the rod 59 extending between the arms, said plate 58 being provided with curved arms 60, similar in character to the 85 arms 47.

On the inner side of the legs 11 are plates 61 and 62 forming guideways in which slides a transverse plate 63, provided with vertical slots 64 near each end thereof, in 90 which slots work the ends 65 of the cam arms 66 fastened to the shaft 39 at either end thereof. Intermediate the ends of the cam arms 66 are mounted the lower ends of links 67, the upper ends of which are 95 slotted at 68 to work on the rod 69 extending between and connecting the ends of the crank arms 54. A pin 70 in each of the legs 11 limits the downward movement of the plate 63, while springs 71, fastened one 100 end to lugs 72 at each end of the plate 63 and the other end to the legs 11 urge the plate 63 into its lowermost position. At each end of the top of the plate 63 is fastened, by screws 73 or in any other suitable manner, the upwardly extending forked twisting elements 74, (see Figs. 6 and 7).

The operation is as follows: with the devices in the position shown in Fig. 3, a stick of candy 100 is rolled down the table 110 26, the treadle (not shown) released, when the parts automatically come into the position shown in Fig. 3, the stick of candy 100 being rotated in an anti-clockwise direction by the wheels 18, 20 and 54. The strip of 115 paper 32 is moved from left to right diagonally across the table 26 when the corner thereof will be engaged by the wheels 18, 20 and 54 and the wrapping operation begins. At this point, the treadle is depressed 120 slightly, whereupon the link 38 pulls down the lever 35 to operate the cutter 37 and sever a length of paper from the strip 32. This downward movement of the lever 35 during the cutting operation does not affect 125 the remainder of the devices, because of the slotted connection between the links 48 and 67 and their respective devices. The severed length of paper is wrapped around the stick of candy 100 and projects outward 130

from each end thereof. The treadle is now still further depressed when the ends 65 of the cam arms 66, engaging with the upper ends of the slots 64 move the plate 63 and 5 attached twisting devices 74 upward into engagement with the projecting ends of the length of paper on the stick of candy 100, the stick of candy being meanwhile rotated by the wheels 18, 20 and 54. Continued depression of the treadle causes the end of the slots 68 in the links 67 to engage with the rod 69 and rotate the crank arm 52, whereupon the long arm 51 moves the shaft 53 and wheels 54 upward out of engagement 10 with the stick of candy, causes pins 57 to engage with the plate 58 to move the curved arms 60 upwardly, and, by the pin on the arm 35 engaging the bottom of the slot 49 in the link 48 to cause a rotation of the arms 20 45 on the shaft 17, moving the plate 46 downward and the curved arms 47 upward to throw the wrapped stick of candy 100 onto the inclined table and out of the machine. The above described sequence of operations 25 may be repeated indefinitely.

I may, if desired, feed the paper strip automatically, though I have described it as being fed by hand. Further, though I have described the preferred embodiment of 30 my invention somewhat in detail, it is to be understood that I may vary the details of the construction and arrangement of parts shown within comparatively wide limits without departing from the spirit of the invention.

Having thus described my invention, what I claim as new and desire to secure by Letters Patent, is:

1. In a wrapping machine, the combination of an inclined table, yielding guides 40 mounted on each side of said table, a passageway between the guides and the table to permit the passage of a strip of paper therethrough, a cutting edge at one side of the table, and a pivotally mounted cutter 45 cooperating with said cutting edge to sever the strip of paper passing between the guides and the table.

2. In a wrapping machine, the combination of a plurality of parallelly arranged 50 shafts, a plurality of spaced wheels thereon defining a trough for receiving a stick of candy or the like, an inclined table, over which the candy is fed to the trough, a second inclined table over which the candy 55 is fed out of the machine, a supplementary table interposed between the second table and the trough, curved arms projecting from said supplementary table and lying normally below the trough and between the 60 spaced wheels, and means for tilting the second table to throw the candy out of the trough onto the table.

In testimony whereof, I have signed my name to this specification, in the presence of 65 two subscribing witnesses.

FRANK BEN LANTERY.
